Primary Examiner — Holly E Thurman*Assistant Examiner* — Altaira J Swangin(74) *Attorney, Agent, or Firm* — Kilpatrick Townsend & Stockton LLP(57) **CLAIM**

The ornamental design for keyboard, as shown and described.

DESCRIPTION

FIG. 1 is a perspective view from the upper front, right side of the keyboard showing our new design.

FIG. 2 is a perspective view from the upper back, left side thereof;

FIG. 3 is top plan view thereof;

FIG. 4 is a bottom plan thereof;

FIG. 5 is a front elevation view thereof;

FIG. 6 is a back elevation view thereof;

FIG. 7 is a left side elevation view thereof; and,

FIG. 8 is a right side elevation view thereof.

The broken lines depict portions of the keyboard that form no part of the claimed design.

1 Claim, 5 Drawing Sheets(56)
